United States Patent Office

Des. 196,381
Patented Sept. 24, 1963

196,381

CLAM OPENER

Carmelo S. Basilotta, 35—42 80th St.,
Jackson Heights, N.Y.

Filed Apr. 19, 1963, Ser. No. 74,524

Term of patent 14 years

(Cl. D44—29)

FIGURE 1 is a side elevational view of a clam opener showing my new design;

FIGURE 2 is a top plan view;

FIGURE 3 is a side elevational view taken from the side opposite that shown in FIGURE 1 and with the opener in inverted position;

FIGURE 4 is a bottom plan view; and

FIGURE 5 is a sectional view taken on the line 5—5 of FIGURE 2.

I claim:

The ornamental design for a clam opener, as shown.
